UNITED STATES PATENT OFFICE.

ROBERT ELCOCK, OF JOHANNESBURG, TRANSVAAL, SOUTH AFRICA.

PERMUTATION LOCK.

Application filed June 2, 1921. Serial No. 474,539.

To all whom it may concern:

Be it known that I, ROBERT ELCOCK, a subject of the King of Great Britain, residing at Victoria Mansions, Eloff Street, 5 Johannesburg, Transvaal, Province of the Union of South Africa, have invented certain new and useful Improvements in Permutation Locks; and I do hereby declare the following to be a full, clear, and exact description of the invention, such as will enable others skilled in the art to which it appertains to make and use the same.

The present invention relates to permutation locks, one object of the invention being to construct a lock which, whilst being of simple construction, provides a large number of combinations and is practically incapable of being opened by feeling for the gates of the various rings forming 20 the combination.

For the sake of convenience the lock will be described and illustrated in the accompanying drawing as applied to cycle steering heads but it will be obvious that its application is general and is not limited to this particular purpose.

Fig. I is a longitudinal sectional view.

Fig. II is a transverse section on the line A A, looking in the direction of the arrow. 30 Fig. III is a transverse section on the line B B looking in the opposite direction to Fig. II.

Fig. IV shows an alternative form of construction of the rings.

Fig. V shows a lock fitted with a key.

Fig. VI shows details of the key plate.

1 indicates the fixed tube and 2 the rotatable tube of a steering head.

A seating 3 is secured to the tube 1 in 40 any convenient manner, preferably by the device described in my Patent No. 1,405,987, dated Feb'y 7, 1922. In the drawing it is shown as an integral part of the fixed tube.

45 A casing 4 is secured to the seating, for example by means of screws 6 the heads of which are filed off flush with the surface. Or the casing may be made to screw onto the seating and locked by means of a grub 50 screw, which is covered by the head 11 and is only exposed when the device is in the unlocked position.

In the top of the casing is formed an annular groove 7 in which lies a flat spring 55 but this is not essential and can be dispensed with if desired.

Through the centre of the end of the casing passes the bolt 8 which also passes freely through the centres of the combination rings 9 and 10. The bolt itself is therefore free for rotational movement and carries at its outer extremity a head 11 graduated along its edge 12 so that its movement with regard to the casing 4 can readily be determined.

60 Rigidly secured to the bolt 8 is a ward 13, and the whole bolt is forced outwards by the action of the spring 14 arranged between the outer face of the end of the casing 4 and the inner face of the head 11. 70

The ward 13 is therefore in contact with the face of the combination ring 10. This ring is free to rotate in the casing 4 and is provided with a cylindrical extension 15 which bears against the seating 3 and prevents lateral movement. The ring 10 has a gate 16 and the face, which is in contact with the ward 13, is provided with a number of serrations 17.

75 Carried inside the ring 10 and fitting closely thereto is another permutation ring 9 having a gate 18. The back of this ring is formed with a flange 19 which fits into a recess in the ring 10 but is smaller in diameter than the recess so that an annular space 20 is left between the two rings. The flange 19 carries a projection 21 and the flange of ring 10 also carries a projection 22, extending radially into said annular space 20 so that the ring 9 can drive 90 the ring 10 when the two projections come into contact.

80 Projecting from the face of the ring 9 is a stud 23 which supplies the means for moving the ring 9 or the rings 9 and 10 95 together. It will be seen that, when the head 11 is revolved without pressing it in against the action of the spring 14, the ward 13 is in contact with the serrations 17 on the ring 10. This ring therefore revolves 100 with the head 11, bolt 8 and ward 13, and sooner or later carries ring 9 with it, and it is clear that no amount of rotational movement will bring the ward 13 any nearer to the gate 16.

105 The only way in which this can be done is to press in the head 11 when the ward 13 is thrown out of engagement with the serrations 17. In this position, however, it is obvious that no feeling for the gate can 110 take place since the ward is out of engagement altogether with the combination rings.

It will further be seen that it is not necessary to set the combination in order to shoot the bolt, when in the unlocked position.

The operation of withdrawing the bolt 5 is performed as follows:—

The head 11 is pressed in and given at least two full turns in one direction, say in a clockwise direction. This ensures that the stud 23 and ward 13 and projections 21 10 and 22 are respectively in contact. The head is then turned, still in a clockwise direction until a certain figure registers with a datum mark on the casing 4. The ring 10 and so the gate 16 is thus placed in a 15 certain predetermined position.

The head is then turned in an anti-clockwise direction, the ward 13 moving the inner ring 9 only, until a certain figure on the head 11 registers with the datum mark. The 20 ring 9 is then in such a position that the gate 16 registers with the gate 18. The head is again turned in a clockwise direction until a predetermined number registers with the datum mark. In this position the ward is 25 immediately over the gates and on releasing the pressure on the head it is free to enter the gates thus allowing the bolt 8 to be withdrawn under the influence of the spring 14.

It will be apparent from the foregoing description that more than two permutation rings can be used, also that the bolt can be shot at any position of the head, since in the unlocked position the ward cannot get out of engagement with the gates in the 35 combination rings.

Further the rings may be made so as to spring into each other and into the casing 3 as shown in Fig. IV. This form of construction enables the lock to be made very 40 compact and at small cost.

In the example shown, there are three rings *a*, *b* and *c*, having a substantially concave shape on their outer periphery. Rings *a* and *b* have a convex shape round their 45 inner periphery to engage with the concave peripheral surfaces of rings *b* and *c* while the concave peripheral surfaces of ring *a* engages a convex projection *d* on the casing 3.

Moreover the accuracy of the lock can be controlled by means of the width of the gates, that is to say if a very accurate setting is desired the gates will only be just wide enough to receive the ward, whereas 55 if no great accuracy is desired the gates may be made much wider than the ward.

The lock as described is in its simplest form; it will be obvious that by increasing the number of rings it can be made more 60 complicated and correspondingly difficult to tamper with.

There may be cases where it is desired to open such a lock by means of a key. The action of a lock having two combination 65 rings depends, as has already been indicated,

upon three consecutive angular movements in opposite directions. It is therefore necessary to devise a key which will permit of these three definite movements only. Such a device is shown and explained by reference to Figs. V and VI of the drawings. 70

A ring 24 is formed on the head 11 and the key 25 is so shaped that when it is in position it retains the head 11 sufficiently pressed in as to ensure that the ward 13 is always out of engagement with the serrations 17. The first condition for unlocking is thus fulfilled. The key is held in position by any suitable means, for example by feathers 26 and 27 fitting in the corresponding groove in the casing 4 and tube 1 respectively. The end of the key is formed in a U shape 28, the width of the U being sufficiently great to permit of movement of the ring 24 towards the tube 1. Stops 29^a, 29^b, 29^c, 29^d and 29^e are provided on the ring 24 so that they engage with the key and prevent rotation of the head 11 beyond a certain point. In order that it may not be possible readily to detect the angular movements required by a comparison of the stops with the graduations on the head, any number of dummy stops may be provided. 80

In the key is a slot 30 and in connection with the stops 29^a, 29^b, 29^c, 29^d and 29^e are inclined portions 31^a, 31^b, 31^c, 31^d and 31^e which are staggered relatively to one another. The action of the key is as follows:— It is first applied to the lock by pressing in the head 11 and placing the ring 24 in the U piece 28 and inserting the feathers 26 and 27 in the slots on the casing and tube. The head 11 is then pressed in as far as possible and given at least two turns in a clockwise direction in the same manner as when the lock is used as an ordinary combination lock, and is left so that the zero mark on the head registers with the key. 100

The ring is now in the position shown in Fig. VI. The head is now given a further turn in the clockwise direction and the stop 29^a encounters the key. The part 31^a enters the slot 30 and further movement is prevented by the perpendicular face 32^a coming in contact with the key. The head is now turned in an anti-clockwise direction and encounters the stop 29^e which is a dummy and has no action in stopping the rotation of the head since the part 31^e does not come opposite the slot 30. It therefore acts as a wedge against the inner surface of the U shaped portion of the key 25 and the head is forced further towards tube 1 thus throwing the stop 29^e clear of the key. The rotation of the head is continued and the stop 29^b passes the key for the same reason as did 29^a. 110 It also passes dummy stops 29^d and 29^e being finally stopped by 29^a, part 31^a entering the slot 30. The head is then turned in a clockwise direction when it passes the dummy 120 125 130

- stops 29^c and 29^d being stopped by 29^b. The ward and combination rings are now so arranged that on removal of the key the lock opens.
- 5 This is the simplest form of the invention. I may, however, provide more than one slot 30 in the key and more than one series of inclined faces in order to render the discovery of the combination more difficult. I 10 may also make the graduations round the head unequal in size but not to such an extent as to be apparent. This would have the effect of upsetting the calculations of anyone who might endeavour to find the angles 15 through which the ward has to be moved, by comparison of the marks on the stops, which might appear through long use, and the graduations on the head.
- The lock can therefore be used as a combination lock or it can be used in conjunction with a key, differing, however, from an ordinary key lock in that no aperture in the lock itself is necessary in which to insert the key, and in that the key remains stationary 20 while the lock is turned. Where a number of locks are in use the differences between the angles through which it is necessary to turn any one head can be made the same, but the first angle through which the head is 25 turned can be made to vary with any one lock. Under these circumstances the same key and similar key plates can be used for all the locks the combinations of which however will be different.
- 30 Or all the locks can be made with differing angles and the positions of the stops on each key plate altered accordingly. Again one master key can be used to open all the locks.
- 35 Furthermore the lock is damp and dust-proof under ordinary conditions owing to the overlapping of the head 11 on the casing 4.
- It may here be stated that a lock and key 40 constructed according to this invention has actually been made and is working most satisfactorily. It will be understood that the head is rotatable at all times whether the bolt is shot or not and this renders it particularly suitable for use in conjunction with 45 valves.
- I claim:
1. In a combination lock, the combination of a casing, a bolt, a ward on the bolt, a head secured to the bolt and rotatably and slidably mounted on the casing, a plurality of rotatable combination rings and means rendering the ward and one of the rings incapable of relative movement to set the combination when the bolt is in the locked position without a preliminary longitudinal movement of the bolt.
  2. In a combination lock, the combination of a casing, a bolt, a ward on the bolt, a head secured to the bolt, a plurality of 55 rotatable combination rings, serrations on the face of one of said rings and a spring whereby the ward is normally forced into contact with the serrations on the ring.
  3. In a combination lock, the combination of a casing, a bolt, a ward on the bolt, a head secured to the bolt, a plurality of combination rings adapted to fit one inside another to provide an annular recess therebetween, a radially disposed lug on each of 60 said rings designed to operate within the recess, serrations on the face of the outer ring and a spring whereby the ward is normally forced into contact with the serrations on the ring.
  4. In a combination lock, the combination of a casing, a bolt, a ward on the bolt, a head secured to the bolt and rotatably and slidably mounted on the casing, a plurality of rotatable combination rings, a spring 65 adapted to keep said ward in contact with said rings and means whereby any rotational movement of the head when the bolt is in the locked position is rendered ineffective to set the combination without a preliminary and sustained longitudinal movement of the bolt against the action of the said spring.
  5. In a combination lock, the combination of a casing, a bolt, a ward on the bolt, a head secured to the bolt and extending 70 around the exterior of the casing, a plurality of combination rings all of which are free to move relative to the casing, means on the inner ring whereby the ward can drive it, means whereby any ring can transmit its 75 movement to the adjacent outer ring, serrations on the face of the outer ring and a spring housed between the end of the casing and the inner face of the head and adapted to force the ward into contact with 80 said serrations.
  6. In a combination lock, a bolt restrained in the locking position by means of a plurality of relatively rotatable rings, one of said rings being provided with a serrated 85 face and the other with a depending lug, a ward on the bolt engageable with said serrations and lug, each ring having a gate, which gates are brought into alignment so as to allow the ward to pass into the gates 90 and thus bring the bolt to the unlocking position, by means of a graduated outer head rigidly secured to the bolt and free to revolve on the casing enclosing said rings and bolt.
  7. In a combination lock, a bolt restrained 95 in the locking position by a plurality of relatively rotatable rings, a casing, one of said rings being provided with a serrated face, enclosing a ward on the bolt, a spring adapted to keep said ward engaged with the 100 said serrations, each ring having a gate which gates are brought into alignment so as to allow the ward to pass into the gates 105 and thus bring the bolt to the unlocked position by means of a graduated outer 110

- head rigidly secured to the bolt and free to revolve on the casing enclosing said rings.
8. In a combination lock the combination of a casing, a bolt, a ward on the bolt, a 5 slideable and rotatable head secured to the bolt and extending around the exterior of the casing, a plurality of combination rings all of which are rotatable relative to the casing, each ring having a gate which gates 10 are brought into alinement so as to allow the ward to pass into the gates and thus bring the bolt to the unlocking position by means of the said head, the arrangement of the parts being such that in the unlocked 15 position the rings are all held by the ward in the set position to enable the bolt to be locked whatever the position of the head.
9. In combination with a combination lock having a fixed casing and a rotatable head, 20 a key mounted on the casing in proximity to said head, said head being provided with a plurality of stops engageable with the key whereby the head can be given a plurality of successively opposing rotational 25 movements through definite angles, these angles being automatically determined by the stops coming into contact with the key and preventing further movement in that particular angular sense.

10. In combination with a combination lock having a fixed casing and a rotatable head, a key adapted to fit onto the casing, a ring extending around said head, a plurality of stops on said ring, inclined faces on the stops and a gate in said key, certain of the inclined faces being so arranged and of such a width that they will enter the gate in the key and certain of the inclined faces being so arranged and of such a width that they will not enter the gate in the key but 40 force the head into such a position that the stops pass the key.

11. In combination with a combination lock having a fixed casing and a rotatable bolt movable longitudinally therethrough, and a head carried by the bolt, a ring mounted upon the rotatable head, a plurality of stops arranged on said ring, said stops being provided with inclined faces of varying width, a key mounted on the casing and engaging with the ring, the key continually holding the ring in a partially depressed position, and a gate in the key, certain of the inclined faces being so arranged and of such a width that they will enter 50 the gate in the key.

In testimony whereof I affix my signature.
ROBERT ELCOCK.
